(57) **CLAIM**

The ornamental design for bridged mini-bulkheads, as shown and described.

DESCRIPTION

FIG. 1 is a first perspective view of bridged mini-bulkheads, showing my new design. The view is taken from a top, front and right side.

FIG. 2 is a second perspective view of the bridged mini-bulkheads of FIG. 1. Here, the view is taken from a bottom, rear and left side.

FIG. 3 is a top plan view of the bridged mini-bulkheads of FIG. 1. Features that were shown in dashed lines in FIGS. 1 and 2 have been removed for clarity.

FIG. 4 is a bottom plan view thereof.

FIG. 5 is a front plan view thereof.

FIG. 6 is a rear plan view thereof.

FIG. 7 is a right side elevation view thereof; and,

FIG. 8 is a left side elevation view thereof.

The broken lines in the drawings depict portions of the bridged mini-bulkheads that form no part of the claimed designs. Particularly, in FIGS. 1 and 2 the electrical wires on the end are included simply to show environment.
